UNITED STATES PATENT OFFICE

HARRY SEBELL, OF BOSTON, MASSACHUSETTS, ASSIGNOR TO ARTHUR H. PARKER, OF LEXINGTON, MASSACHUSETTS

CAN

Application filed November 21, 1928. Serial No. 320,978.

This invention relates to a tin can or container of the type which is sealed through the medium of a U-shaped sealing strip which embraces sealing flanges formed on the can body and the cover respectively.

One of the objects of the invention is to provide an improved can of this type which is so constructed as to facilitate the removal of the sealing strip preliminary to opening the can. This is accomplished by providing the cover of the can with a tab which is integral with the sealing flange of the cover and extends from the periphery of said flange, said tab being folded back against the flange and confined between said flange and the sealing strip adjacent one end of the latter. When the can is sealed the end of the tab is exposed so that by pulling outwardly on the tab the sealing strip will be loosened thereby facilitating its removal. Since the tab is integral with the cover said tab may also be used as a means for loosening the cover from the mouth of the can after the sealing strip has been removed.

In order to give an understanding of the invention I have illustrated in the drawings a selected embodiment thereof which will now be described after which the novel features will be pointed out in the appended claims.

In the drawings:

Fig. 1 is a perspective view of the upper portion of a can embodying my invention;

Fig. 2 is a fragmentary sectional view;

Fig. 3 is a fragmentary sectional view showing the manner in which the tab is used for loosening the sealing strip;

Fig. 4 is a view illustrating the manner in which the tab is used for removing the cover from the can;

Fig. 5 is a view of the blank from which the cover is made;

Fig. 6 is a perspective view of the cover before it is applied to the can.

In the drawings 1 indicates a can body which is open at one end and 2 indicates the cover or closure by which the can is closed. The can herein shown is of that type in which the cover is sealed to the can by means of a U-shaped sealing strip which em-

braces sealing flanges on the can and cover respectively.

The sealing flange on the can is shown at 3 and the mating sealing flange on the cover is shown at 4. 5 indicates the U-shaped sealing strip which embraces these sealing flanges and by which the can is sealed.

In the particular construction shown the cover 3 is formed with the upstanding curb or wall 6 which fits into the open end of the can and it is also formed with the locking flange 7 which overlies the upper leg 8 of the sealing strip 5, said locking flange 7, the sealing strip 5 and the sealing flanges 3 and 4 being pressed firmly together in the process of sealing the can.

A seal of this type is an exceedingly effective one so far as sealing the can is concerned but the can is sometimes a little difficult to open because of the difficulty encountered in loosening the sealing strip. It is the principal object of my present invention to provide a novel construction by which the loosening of the sealing strip may be facilitated thereby making the opening of a sealed can an easy operation.

In accordance with my invention I form the sealing flange 4 of the cover with an integral tab member 9 which, during the sealing of the can, is folded into the space between the locking flange 7 and the sealing flange 4 and is thus folded around the upper leg 8 of the sealing strip, said tab being of sufficient length so that the end 10 thereof is exposed.

In the operation of sealing the can the can cover will be so positioned on the can that the tab 9 will be located adjacent one end 11 of the sealing strip 5. When the can is to be opened the end 10 of the tab is separated from the can and then a pulling strain is applied to the tab. Since the tab is bent around the leg 8 of the sealing strip adjacent the end 11 thereof the pulling strain on the tab will pull said end 11 of the sealing strip out from its sealing position, as shown by dotted lines in Fig. 3, thereby loosening said sealing strip so that it can be readily grasped and removed entirely from the can.

After the sealing strip is removed the tab 9 may then be employed as means for with-

drawing the cover from the can. The cover is made so that the upstanding curb 6 thereof sets into the mouth of the can and frictionally engages the latter. Since the tab 9 is integral with the sealing flange of the cover an upward pull on the tab 9 will result in pulling the cover from the can and thus opening the latter.

I will preferably provide the tab with an opening 12 into which an implement 13, such for instance as an ice pick or the tine of a fork, may be inserted as shown in Fig. 4, said implement providing means by which an increased pulling strain can be applied to the tab. The tab 9, therefore, operates as a means both to loosen the sealing strip 5 and also to loosen the cover from the can.

The cover 2 is preferably made from a circular piece of sheet metal as shown at 14, the latter being pressed into the desired shape by means of suitable dies. In carrying out my invention I propose to form the circular blank 14 with the tab 9 extending from its periphery and hence when the can cover is finally shaped it will have this tab 9 integral with the sealing flange 4 and extending from the periphery of the flange, as shown in Fig. 6.

In the operation of applying the sealing strip and finally sealing the can this tab 9 is folded into the space between the sealing flange and the locking flange and will thus be folded around the leg 8 of the sealing strip as shown in Fig. 2.

35 I claim:

1. A sealed can comprising a can body having a laterally-extending sealing flange, a can cover also having a laterally-extending sealing flange which mates that of the can body, and a U-shaped sealing strip embracing said sealing flanges, one of said sealing flanges having a tab integral therewith and extending from the periphery thereof, said tab being folded around one leg of the sealing strip adjacent one end of the latter and having its end exposed, whereby a pulling strain on the tab will loosen the sealing strip.

2. A sealed can comprising a can body having a laterally-extending sealing flange, a can cover also having a laterally-extending sealing flange which mates that of the can body, and a U-shaped sealing strip embracing said sealing flanges, the sealing flange on the cover having integral therewith a tab extending from the periphery thereof, said tab being folded around one of the legs of the sealing strip adjacent the end of the latter and having its end exposed, whereby a pulling strain on the tab will loosen the sealing strip.

3. A sealed can comprising a can body having a laterally-extending sealing flange, a can cover also having a laterally-extending sealing flange mating that of the can body, a U-shaped sealing strip embracing said sealing

flanges, said cover being formed with a locking flange which overlies the sealing strip, and said cover also having a tab integral therewith and extending from the periphery of the sealing flange thereof, which tab is folded around one of the legs of the sealing strip and is confined between said leg and the sealing flange and locking flange of the cover, the end of the tab being exposed, whereby the sealing strip may be loosened by applying a pulling strain on the tab.

In testimony whereof, I have signed my name to this specification.

HARRY SEBELL.
